UNITED STATES PATENT OFFICE.

HARRY A. TOTTEN, OF BURLINGAME, CALIFORNIA.

GOLF TEE AND METHOD OF MAKING SAME.

Application filed February 28, 1927. Serial No. 171,586.

My invention relates to golf-tees.

To replace the moistened-sand tee, which has many objectionable features, not the least of which is the cost of maintenance, several substitutes have been devised in the form of individual structures or bodies adapted to temporarily penetrate the ground and elevate the ball for a drive. But, owing to the nature and environment of the game, both psychological and physical, it has been difficult to regard economy as of any great moment, and the consequence has been that the tees thus substituted, while serving for greater convenience and cleanliness than the moistened-sand tees, have been made of materials and in decorative forms and packing, which have seemed to warrant an excessive charge. A good example of this is the ornamenteally turned tee, in the preparation of which necessarily only one is made at a time, thus involving initial expense; and to this expense is added relatively handsome packing in comparatively small numbers so that by the time it reaches the player, a price per box of a few of these tees is such that only the vanity of the purchaser supports him in the purchase.

The object of my invention is to remedy this difficulty in the interest of economy, and this end I secure by providing a tee the manufacturing cost of which is so small that it is likely to reach the player for a small price or even to be supplied in quantity, gratis, by the club.

The nature of my tee as a new article of manufacture, and the novel method of making it will now be fully described and ascertained in and by the following specification, read in connection with the accompanying drawings in which

Fig. 1 is a perspective view of a block, broken at the back, from which the tees are to be cut.

Fig. 2 is a perspective view of the block of Fig. 1, showing the cutting in the top and bottom, in one direction, of the grooves comprising the ball-supporting sockets of the tees.

Fig. 3 is a perspective view of the block, showing the cutting, in other direction, of said grooves, the intersection of which with the first named grooves completes the ball-supporting sockets.

Fig. 4 is a fragmentary plan of the socketed block being presented to a gang of saws to successively make the oppositely inclined cuts of the tees from the front side. 55

Fig. 5 is a similar plan showing the presentation of the block to a single saw at each end, oppositely relatively inclined and adapted to make the remaining cuts alternately from the ends of the block. 60

Fig. 6 is a perspective view of the completed tee. 65

Fig. 7 is a broken section of the tee showing a ball supported upon it. 65

Fig. 8 is a front elevation of the block, showing it in a holder, and presented to a planer head to form the ball-supporting grooves. 70

Fig. 9 is a front elevation of the block, showing it in a tiltable holder, adapting it to be presented to a gang of saws by which the tees are formed in and cut from the block. 75

Referring first to Fig. 6, it will be seen that the novel tee, which, as a new article of manufacture, I shall herein claim as the product of the novel process also claimed herein, is a pyramidal body 1, polygonal in cross section and having plane sides, three or more in number, here shown, for example, as four. Although in Fig. 6, the tee, with respect to its pyramidal form, is inverted in order, as shown in Fig. 7, to serve its function of penetrating the ground for uprightness, I shall herein refer to its smaller end as its vertex, and to its larger end as its base, notwithstanding that in use as a tee, the smaller is its lower end and the larger is its top. 80

The base of the pyramidal tee 1 is formed with a ball-support 2. This support is of a socket nature, the cavity being formed and bordered by uprising points 3, corresponding in number to the number of the pyramid faces, and are, consequently, here shown as four. These points are angular in cross section, due to intersecting V-grooves made in the process of manufacture, and by reason of such angularity they present internally opposing and downwardly converging ridges adapting them to receive and poise a ball 4 lightly, but with efficient stability. The tee is made of suitable material having in view not only such considerations as availability 95

and adaptability for the use intended, but also economy in substance and in manufacture. In practise it is made of wood.

The method or process of manufacture will now be readily understood.

In Fig. 1, a block 5 is shown which is of wood. It is rectangular and its broken away portion indicates that it may be of any desired size as to length and width, although its thickness will be a standard dimension conformably to the predetermined length of the tee.

The tees are to be formed in and cut out from the block 5; and in shop practise the cutting instrumentalities and the block holder will be so related and relatively adjustable as to dispense with any surface guide markings; but for the present description I have shown such markings in order to make the method clear. Using the ordinary terminology for the faces of a block, namely top, bottom, sides and ends, there are on the top the dotted lines $a-a$. These are parallel with the planes of the ends of the block, and are parallel with each other and equidistant.

Other lines $b-b$ are also on the top, at right angles to the lines $a-a$, parallel with each other, and equidistant by spaces equal to the spacing of said lines $a-a$, so that the top of the block is thus marked off into a plurality of equal squares of a size predetermined for the ball supporting end of the tee. The bottom of the block, not shown, may be marked in the same way as the top.

The front side of the block is marked with lines $c-c$ inclined to the planes of the top and bottom, adjacent lines being inclined in opposite directions, spaced apart and meeting the corresponding lines $a-a$ above and below, in a succession of alternating upright and reversed triangles.

The ends of the block are provided with lines $d-d$, successively oppositely inclined and meeting the lines $b-b$ above and below in a succession of alternating upright and reversed triangles. The block 5 is first subjected to a suitable planer-head which cuts out its top between the lines $a-a$, and then, by reversing the block, its bottom is subjected to said planer-head which cuts it out between the similar lines $a-a$ thereon. Such an operation is indicated in Fig. 8, wherein 6 is the planer-head and 7 is a holder for the block. The cutters 6' of the planer head are triangular ones, so that the grooves 8 in the top and bottom of the block as shown in Figs. 2 and 8 are in section triangular plane-faced V-shaped corrugations. When these cuts are made, the block is turned at right angles to its first position and the planer-head then cuts grooves 9 in the top and bottom between the lines $b-b$ (Fig. 3) with the result, that, as clearly shown in said Fig. 3, there are formed in the top, and in the bottom also, by these intersecting grooves, the

angle-walled depressions, which in Fig. 6 are designated by the sockets 2 and points 3 and which constitute the ball-support of the tee 1.

Referring now to Fig. 4, 10 designates a gang of saws. The block, previously prepared top and bottom, as described, is to be fed up front side to said saws, as indicated by the arrow, so that cuts 11 are made into the block first along the lines $c-c$ inclining in one direction and then along the lines $c-c$ inclining oppositely, said cuts stopping short of the back of the block in order to preserve temporarily a suitable bond. Then, as shown in Fig. 5, the block is fed end-wise alternately to the single saws 10' and 10² whereby cuts 12 are made along the several oppositely inclined lines $d-d$, and these cuts successively sever transverse rows of the tees from the block.

In Fig. 9, I have indicated, more graphically, the saw gang 10, and have shown the blockholder 7 capable of a tilting movement in order to present the oppositely inclined lines $c-c$ to the saws.

It will now be clear that by this method indicated and carried out by such operation, the block will be cut up and separated into a number of polygonal pyramidal bodies, with angular bordered ball supporting sockets in their bases, and with vertexes adapted for readily penetrating the ground. Moreover, this cutting of the block is without waste, and is economical in point of time in that, in contrast, for example with a turning operation involving individual subjection of the work, a multitude of individuals are here produced simultaneously. Also by the cutting herein described, a tee is made with angular body adapted for maximum upright stability when driven into the ground and for ease in penetration; and said tee by its angular socket, presents a support delicately poising the ball.

I claim:

1. A one piece polygonal pyramidal golf tee having in its larger end intersecting grooves providing upstanding points forming between them a ball-supporting socket.
2. A polygonal pyramidal golf tee having in its larger end, intersecting V-grooves forming an angular ball-supporting socket.
3. The method of making the herein described golf tee which comprises cutting out in the top and bottom of a block a plurality of intersecting grooves and then cutting into said block from its sides and ends in planes adapted to divide the block into a plurality of alternately reversed polygonal pyramids each having at one end a penetrating vertex and at the other end a ball-supporting socket formed by the intersection of the grooves.
4. The method of making the herein described one piece golf tee, which comprises cutting out the top and bottom of a block to provide a plurality of depressions and then

cutting into said block from its sides and ends in planes adapted to divide the block into a plurality of alternately reversed polygonal pyramids each having at one end a 5 penetrating vertex and at the other end one of said depressions providing a ball supporting socket.

5. The method of making the herein described one piece golf tee, the step of which

comprises cutting into a block from its sides 10 and ends in planes adapted to divide the block into a plurality of alternately reversed polygonal pyramids each having at one end a penetrating vertex and at the other end affording a means to provide a ball socket. 15

In testimony whereof I have signed my name to this specification.

HARRY A. TOTTEN.
